UNITED STATES PATENT OFFICE.

JAKOB LUND AND HERMANN HAUSAMANN, OF FREDRIKSTAD, NORWAY, ASSIGNEES
TO DE NORDISKE FABRIKER, OF CHRISTIANIA, NORWAY.

POWDERED SOAP AND METHOD OF MAKING SAME.

No Drawing.

Application filed March 19, 1920. Serial No. 367,250.

To all whom it may concern:

Be it known that we, JAKOB LUND, a citizen of the Kingdom of Norway, and HERMANN HAUSAMANN, a citizen of the

5 Swiss Republic, both residing at Fredrikstad, Norway, have invented certain new and useful Improvements in Powdered Soap and Methods of Making Same, of which the following is a specification.

10 Our invention relates to soap and more especially to powdered soap or soap powder and its particular object is a high grade soap powder prepared from liquid oils and fats. Another object of our invention is 15 a method of manufacturing such soap powder in a simple and effective manner.

Heretofore liquid oils and fats, and especially the drying oils, have not been utilized in the manufacture of soap powder for 20 the reason that the soap obtained therefrom was soft and unstable, the addition of great quantities of soda being required to dry them to some extent and put them in a condition in which they are capable of being 25 ground.

We have now ascertained that the soda soaps of liquid oils, fish oils and the like can be easily transformed into products 30 permanently stable and capable of being ground, if they are subjected at high temperatures to a treatment adapted to highly concentrate them. This phenomenon is due primarily to the fact that the concentration is accompanied by chemical 35 conversions which are made evident for instance by a lowering of the iodine titer and probably result in transformations of the non-saturated fatty acids which improve the stability of the soap.

40 The method of manufacturing soap powder from liquid oils and fats according to the present invention accordingly consists substantially in highly concentrating the soap which has previously been obtained 45 from such oils and fats in any well-known manner. The concentration cannot, however, be effected in open vessels for the reason that the soap would burn on to the vessel and would be destroyed.

50 We have now ascertained that, contrary to what could be expected, the concentration can be carried out easily by carefully distilling away water from the soap in an autoclave under increased pressure. In distilling off the water we prefer to apply

temperatures between 180 and 200 degr. C. in order to maintain the concentrated soap in a liquid state. Varying quantities of an alkali may be added if desired.

The temperatures mentioned above exert 60 a favorable influence on soap prepared from impure oils and fats in so far as they cause the coloring matter and the odoriferous constituents of the soap to be distilled over or to be destroyed more easily. The 65 distillation is performed in the following manner. The soap mass is heated in the closed vessel up to about 200° C., and then a steam outlet is carefully opened, so that 70 part of the water can distil off, but the pressure remain constant.

In soap prepared from drying oils, train oils, etc. the combination of the high temperature and the pressure causes chemical 75 reactions to take place (polymerization), necessary for the stability and durability of the soap powder, which through these reactions become quite resistant to the oxidizing influence of the air.

By the simple treatment described above 80 a high-grade light-colored, odourless soap powder of superior cleaning power is obtained from low-grade raw materials.

Such powder is greatly superior to the powder obtained by the atomizing and subsequent evaporation of soap which has not undergone the process of concentration, inasmuch as it is not possible to produce an efficient drying and evaporation of the water 85 from disintegrated ordinary soap, most of the moisture being retained by the coarse crumbs of soap which, moreover, when heated too highly will coalesce and stick together and lose their powdered condition.

90 We claim:—

1. The process of making soap, which consists in saponifying liquid drying fats and oils, heating the saponified mass under pressure and at a relatively high distillation temperature, and allowing the steam 100 thus formed to escape, while maintaining the pressure.

2. The process of making soaps which consists in saponifying liquid drying fats and oils, heating the saponified mass under pressure and up to about 200° C., and allowing the accumulated steam thus formed to escape for a period of time.

3. The process of making soaps, which 110 consists in saponifying liquid drying fats

and oils, substantially with the exclusion of air, continuing the heating under pressure and at a relatively high distillation temperature, and permitting the accumulated steam thus formed to escape for a period of time, while substantially maintaining the pressure.

4. The process of making soap powder, which consists in saponifying liquid drying fats and oils, heating the saponified mass 10 under pressure and at a temperature up to about 200° C., allowing the accumulated steam thus formed to escape for a period of time while substantially maintaining the pressure, continuing the heating until the 15 desired concentration of the saponified mass

is obtained, and reducing the resultant hardened saponified mass to powder.

5. The process of making soaps, which consists in saponifying liquid drying fats and oils, heating the saponified mass in the presence of alkali under pressure and at a temperature up to substantially 200° C., allowing the accumulated steam thus formed to escape for a period of time and maintaining the pressure until the desired concentration of the saponified mass is obtained.

In testimony whereof we affix our signatures.

JAKOB LUND.
H. HAUSAMANN.
